2,136,558

REFRIGERATOR

Charles Manshel, East Orange, N. J.

Application September 20, 1935, Serial No. 41,367

2 Claims. (Cl. 62—89)

This invention relates to improvements in refrigerators, and especially to domestic refrigerators equipped with a mechanical refrigerating system; and the invention has reference, more particularly, to a novel improved form of door for such refrigerators adapted to provide auxiliary supporting means for articles and materials desired to be stored within the refrigerator.

It has been heretofore known to provide article and material supporting shelves or racks upon the inward side of domestic refrigerator doors, but in such arrangements access to the shelves or racks so disposed could only be attained by swinging open the door with consequent wasteful escape of cold air from the main interior or chamber of the refrigerator and a resultant undesired rise of temperature within said interior or chamber.

It is an object of the instant invention to provide a novel structure for closing the main interior or chamber of a refrigerator which is arranged to provide auxiliary supporting means for articles and materials desired to be stored within the refrigerator, but which is further provided with means, manipulatable at will, to give access to such auxiliary supporting means without necessity for opening the main refrigerator door per se.

Another object of this invention is to provide a novel means for normally communicating cold air to and around the auxiliary supporting means, together with means to automatically cut off such communication when such auxiliary supporting means are opened to access from the exterior of the main door, whereby escape of cold air from the refrigerator interior with undesired rise of temperature therein is successfully avoided.

Other objects of this invention, not at this time more particularly enumerated, will be understood from the following detailed description of the same.

Illustrative embodiments of this invention are shown in the accompanying drawings, in which:

Fig. 1 is an outer face view or front elevation of a refrigerator equipped with the novel door structure according to this invention; Fig. 2 is an inner face view of said novel door structure; and Fig. 3 is a vertical longitudinal sectional view, taken on line 3—3 in Fig. 1, but drawn on an enlarged scale.

Fig. 4 is a fragmentary outer face view or front elevation of a refrigerator equipped with a modified arrangement of the novel door structure; and Fig. 5 is a vertical longitudinal sectional view

thereof, taken on line 5—5 in Fig. 4, but drawn on an enlarged scale.

Fig. 6 is a fragmentary outer face view or front elevation of a refrigerator equipped with another modified form of the novel door structure; and Fig. 7 is a vertical longitudinal sectional view thereof, taken on line 7—7 in Fig. 6, but drawn on an enlarged scale, the means giving access to the auxiliary support being shown in open condition.

Fig. 8 is a fragmentary vertical section of still another modified form of the novel door structure according to this invention.

Similar characters of reference are employed in all of the hereinabove described views, to indicate corresponding parts.

Referring to the drawings, the reference character 10 indicates the main body or housing of a refrigerator which is provided in its front wall with a main door opening 11 giving access to the interior chamber 12 of the body or housing. Located within the interior chamber 12 is a suitable cooling unit 13 of a mechanism refrigerating system. Also arranged in suitable disposition within the body or housing interior 12 are a plurality of shelves 14 for the support of articles and materials desired to be stored within the refrigerator. It will be understood that the detail construction of the refrigerator body or housing may be in accordance with known standard practices, whereby desired heat insulating construction and effects are attained.

Supported on the front wall of the refrigerator body or housing 10, by suitable hinges 15, is a main or primary door member 16 adapted to normally fit into the door opening 11, thereby to close the interior chamber 12 of said body or housing. Cooperative latch means 17, of any convenient known form, is provided to hold the door member 16 closed. Around its periphery the door member 16 is provided with a rabbet flange 18 to break the joint between the door member and the marginal portions 19 of the body or housing door opening 11. Preferably the inner or abutting face of said rabbet flange 18 is provided with a gasket strip 20 suitably secured thereto, and adapted to seal the joint between the door member and marginal portions of the door opening when the former is closed. At its interior side the door member is provided with a plurality of recesses 21 which are covered by a suitably attached back-plate 22, so as to be partitioned by the latter from the interior chamber 12 of the refrigerator housing. In Fig. 3 of the drawings three recesses 21 are shown, it will be understood however that, according to the size or capacity of the door mem-

ber 16, the number of recesses may be increased or decreased. Communicating with the respective recesses through the body of the door member 16 from the exterior face or side thereof are access openings 23. Each access opening is preferably bounded by an internally projecting rabbet flange 23'. Manipulatable means are provided for closing and opening each access opening, said means preferably serving to carry suitably formed article or material supporting shelves or racks.

In Figs. 1 to 3, the means for closing and opening the access openings 23 is arranged in the form of outwardly opening vertical swing auxiliary or secondary doors 24; each being bounded around its periphery with an externally projecting rabbet flange 25 to cooperate with the internal rabbet flange 23' of the access opening served thereby so as to form a break joint. Preferably the inner abutting face of the rabbet flange 25 of each secondary door 24 is provided with a gasket strip 26 suitably secured thereto, and adapted to seal the break joints when said secondary doors are closed. Each secondary door 24 is pivotally connected at its bottom margin to the main or primary refrigerator door member 16 by suitable hinge elements 27; and each secondary door is releasably held in normal closed position by any suitable form of manipulatable latch means 28, which is mounted adjacent to its upper free edge and which is provided with an operating handle 29. Each latch means 28 is adapted to cooperate with a fixed latch piece 30 mounted on the main or primary refrigerator door member 16. Suitably affixed to the inner face of each secondary door 24 is a shelf or tray 31 for the support of articles or material desired to be deposited within the recesses 21. The back-plate 22 of the main or primary door member 16 is provided with openings 32 respectively providing communication between the recesses 21 and the interior chamber 12 of the refrigerator body or housing 10. Cooperative with each said opening 32 is a closure plate 33 which is pivotally connected by spring hinge members 34 to the back-plate 22 so as to close the opening 32, while nevertheless being yieldable to opening movement toward the interior chamber 12 of the refrigerator body or housing 10. It is preferable to provide a sealing gasket 35 around each opening 32, which gasket is engageable by the closure plate 33 when in closed position, to thereby effect a tight joint. Fixed on the recess facing side of each closure plate 33 is a projecting push-piece 36. When a secondary door 24 is closed, the shelf or tray 31 carried thereby will strike the push-piece 36 and thus impart an opening movement to the closure plate 33, thus opening communication between the interior chamber 12 of the refrigerator body or housing 10 and the recess 21 served by the thus closed secondary door 24. Under these circumstances cold air from the interior of the refrigerator is admitted to said recess 21 for circulation therein and around the articles or materials supported therein by the shelf or tray 31. When, however, it is desired to gain access to the articles or materials, and to such end the secondary door 24 is opened and swung outward, the shelf or tray 31 is carried away from the push-piece 36 by the opening movement of the secondary door 24, and consequently the spring hinge members 34 will press the closure plate 33 into closed relation to the back-plate opening 32, thereby cutting off communication between the thus outwardly opening recess 21 and the interior of the refrigerator, so

that cold air from the latter cannot escape and be replaced by warm exterior air resulting in wasteful and undesired rise of temperature within the main interior of the refrigerator. From the above it will be apparent that each of the 5 plurality of recesses with which the primary door member 16 of the refrigerator is provided is subject to selective individual access from the exterior of the refrigerator, without disturbing refrigeration conditions in either the other recesses 10 or the main interior of the refrigerator.

The secondary doors 24 may be modified for operation in manner other than the above described vertical swinging arrangement thereof. For example, the secondary doors 24 may be arranged for movement in the manner of horizontally sliding drawers, as shown in Figs. 4 and 5. When so arranged, telescoping sliding extension brackets 37 may be utilized in place of hinges, and a latching means 38 adapted for top 20 and bottom latching effect may be employed to hold the doors 24 in normally closed relation to the main or primary refrigerator door member 16. In other respects the construction is substantially the same as already above described. As 25 a further example of possible variation in the manner of mounting the secondary doors 24, there is shown in Figs. 6 and 7 of the drawings, an arrangement providing for horizontal swinging movement thereof. In such arrangement, 30 hinge elements 39 connect one vertical end of the secondary door 24 to the main or primary refrigerator door 16, and cooperative latching means 40 are provided at the opposite or free vertical end of the so arranged secondary door. 35

Referring to Fig. 8 of the drawings, there is shown therein a modified arrangement of means for automatically opening and closing communication between a recess 21 of the primary door member 16 and the main interior of the refrigerator when a secondary door 24 is manipulated. In this modified arrangement, the back-plate 22 on the primary door member 16 is omitted, but pivotally suspended from the free side of the shelf or tray 31' carried by the secondary door 24, by means of hinge elements 41 is a closure plate 42. In operation, when the secondary door 24 (which is of the vertical swing type) is swung open, the pivotally suspended closure plate 42 is carried upwardly and inwardly into the recess 21 until it abuts the marginal portions of the rabbet flange 24 surrounding the access opening 23, thus closing the latter against escape of cold air from or entrance of warm air into the main interior of the refrigerator, all as shown by 50 broken lines in said Fig. 8 of the drawings. Preferably a sealing gasket 43 is provided around the access opening 23 to be engaged by the abutting closure plate 42, to thereby form a tight joint when the latter is closed over said access 60 opening 23.

It will be obvious that many changes, other than those above suggested, could be made in the above described constructions, and many apparently widely different embodiments of this 65 invention could be made without departing from the scope thereof as defined by the following claims. It is therefore intended that all matter contained in the above description or shown in the accompanying drawings shall be interpreted 70 as illustrative and not in a limiting sense.

Having described my invention, I claim:—

1. In a refrigerator comprising a housing providing an interior chamber having a door opening leading thereto, a primary door member 75

movable to open and close said door opening, said primary door member having a recessed portion at its inner side, means to partition said recessed portion from the interior chamber of said refrigerator housing, said partitioning means having an opening to establish cool air communication between the interior chamber of said refrigerator housing and said recessed portion, said primary door member having an exterior access opening leading into said recessed portion, a secondary door movable to open and close said access opening, means affixed to the inner side of said secondary door to support material within said recessed portion, a spring-actuated closure plate to close said communication opening when said secondary door is opened, said closure plate having a projecting push-piece engageable by said supporting means when the latter is positioned by the closed secondary door within said recessed portion whereby said closure plate is opened when said secondary door is closed.

2. In a refrigerator comprising a housing providing an interior chamber having a door opening leading thereto, a primary door member mov-

able to open and close said door opening, said primary door member having a plurality of segregated recessed portions at its inner side for storing material at the inner side of said door, means to partition said recessed portions from the interior chamber of said refrigerator housing, said partitioning means having openings respectively communicating between said recessed portions and said interior chamber of the refrigerator housing, said primary door member having exterior access openings corresponding to said recessed portions, independently manipulatable secondary doors cooperative with said access openings, means affixed to said secondary doors to support material within the corresponding recessed portions, a spring-actuated closure plate for the communication opening of each recessed portion to close said opening when the corresponding secondary door is opened, each closure plate having a projecting push-piece for opening the same engageable by the material supporting means carried by a corresponding secondary door when the latter is closed.

CHARLES MANSHEL.
